UNITED STATES PATENT OFFICE

2,432,764

CONTAINER

Stanley B. Jenkins, Boston, Mass.

Application November 23, 1944, Serial No. 564,874

1 Claim. (Cl. 132—84)

1

My present invention relates to containers and more particularly to a combination container for toilet articles such as tooth powder and a tooth brush.

The principal object of my invention is an improved combination container;

Another object is a combination container having two or more compartments having a common swivel cover;

Still another object is a combination container having a common swivel cover which is connected to a removable top member which acts as a tight cover to one of said compartments when the said cover is in a closed position, and

Other objects and novel features comprising the construction and operation of my invention will be apparent as the description of the same progresses.

In the drawings illustrating the preferred embodiment of my invention:

Fig. 1 is a plan view of the container;

Fig. 2 is a side elevation thereof, and

Fig. 3 is a cross-section taken on the line 3—3 of Fig. 1.

Referring more in detail to the drawings, 10 indicates the main compartment of the container and 11 indicates a second compartment. Both compartments 10 and 11 are preferably made as a single unit, such as a plastic molding. Compartment 10 is designed to hold tooth powder while compartment 11 may be used to hold a tooth brush. It will be noted that compartment 11 is ventilated at the top by means of the openings 12 and at the bottom by the openings 13, the said openings making it possible for air to circulate up around any article in the compartment 11, as the case may be. At 14 I have indicated a cover portion which is composed of a cylindrical portion 15 which fits snugly in the upper open end of the compartment 10. Pivoted by means of the screw 16 to the top surface of the portion 15 of the cover 14 is an upper portion 14a of the cover. Also located in the portion 15 is an opening 17 which is designed to be closed when the pivoted portion 14a of the cover 14 is in the positions shown in Figs. 1 and 3 but when the pivoted portion 14a is swung around to the proper position the opening 18 may be made

2

to register with the opening 17 so that powder or other contents located in the compartment 10 may be shaken out. Also the pivoted portion of the cover 14a closes the top of the opening to the compartment 11 when the cover is in the closed position, as shown in the drawings.

The entire top cover member comprising 14, 14a and 15 may be drawn up out of the compartment 10 when it is desired to open this compartment to refill the container or for other purposes.

It is also quite apparent that while I have described the container for use with tooth powder and a tooth brush yet any other suitable articles may be substituted therefor and still be covered in the spirit of the invention.

Having thus described my invention, what I claim as new is:

An improved dispenser container for tooth brushes and tooth powder comprising a unitary casing separately housing said tooth brushes and said tooth powder, a removable closure member located in the upper end of the powder portion of the casing, an outlet port located in said closure, an upper swivel cover member pivoted to said closure and having an outlet port, said swivel cover having an extension portion covering the top of said tooth brush portion of said casing, the outlet ports on said closure and said swivel cover being out of register when the said tooth brush portion of said casing is closed, means for ventilating said tooth brush portion of said casing.

STANLEY B. JENKINS.
